UNITED STATES PATENT OFFICE

FRED C. WHITE, OF MASON CITY, IOWA

BRUSH

Application filed October 5, 1932. Serial No. 636,398.

This invention relates to brushes, and more particularly to an attachment for scrubbing brushes.

The invention consists in the provision of 5 an attachment capable of being readily applied to a conventional scrubbing brush whereby the brush is converted from an ordinary hand brush to what is known as a fountain brush.

10 The invention comprises a handle adapted to be readily attached to the brush and provided with a chamber for holding a cleaning agent, together with valve means controlling the flow of the cleaning agent to the bristles 15 of the brush.

The invention also provides for a feeding of clean or clear water to the bristles of the brush for rinsing purposes.

20 The invention together with its numerous objects and advantages will be best understood from a study of the following description, taken in connection with the accompanying drawings wherein:

25 Figure 1 is a side elevational view of a brush having my attachment applied thereto.

Figure 2 is a sectional elevational view through the attachment.

30 Figure 3 is a sectional view taken substantially on the line 3—3 of Figure 1.

Figure 4 is a perspective view of a valve core.

35 Figure 5 is a transverse sectional view taken substantially on the line 5—5 of Figure 2.

Figure 6 is a sectional view taken substantially on the line 6—6 of Figure 2, and

Figure 7 is a perspective view of a handle member for the valve core.

With reference more in detail to the drawings it will be seen that the attachment is in 40 the nature of a handle adapted to be readily secured to a brush, such as a scrubbing brush illustrated in the drawings and designated generally by the reference character 10. The attachment per se comprises a tube 11 of suitable length, and of suitable material, and provided at one end with a screw cap 12, and at its other end with a plug 13 screw threadedly engaged with the cylinder 11 as at 14. The plug 13 at its free end is beveled as at 15, and 45 is adapted to be secured at the end 15 to the

top of the brush 10 so that the handle will extend at an acute angle to the brush 10 as clearly shown in Figure 1.

The manner of securing the plug 13 to the brush 10 will be hereinafter more fully described.

Extending through the plug 13 at right angles to the bevel 15 is a threaded aperture 16 which is adapted to accommodate a valve, the latter including a casing 17 screwthreaded through the opening 16 and having that end thereof projecting beyond the bevel face 15 adapted to extend through an opening in the brush 10 and to have a nut 18 engaged therewith for securing the plug 13 to the head 60 65 10. The plug 13 is also provided with a suitable aperture 19 for accommodating a screw or other similar fastening means to further insure a positive connection between the plug 13 and brush 10. At its other end the casing 70 75 17 is provided with a gland nut 20 that is apertured to accommodate the stem 21 of a hollow valve core 22 that is arranged in the casing 17 for rotation. A sleeve 23 is threaded into the first named end of the casing 17 and abuts the adjacent end of the core 22 to restrain the core against longitudinal movement relative to the casing 17.

The valve core 22 is provided on one side thereof with an opening or port 24 adapted to register with a port 25 provided in the wall of the casing 17 and normally aligned with an opening or passage 26 provided in the plug 13 for communicating or connecting the casing 17 with the chamber 27 formed by 80 85 the cylindrical portion 11 of the handle.

On a relatively opposite side thereof the valve core 22 is provided with a similar opening 28 adapted to be brought into registry with an opening 29 provided in the valve casing 17 and aligning with a passage or opening 30 provided in the plug 13 and also communicating the casing 17 with the chamber 27. It will thus be seen that when the parts are in the position shown in Figure 2, ports 24, 25 are in registry, while port 28 is out of registry with the port 29 and this will of course prevent the passage of fluid through the passages 26, 30 to the valve at the same time.

A pipe 31 extends through the chamber 27 and at one end is threaded into the passage 26 in the plug 13. At its other end the pipe 31 extends through an opening in cap 12 and 5 is adapted to be coupled as at 32 with a flexible hose 33 leading from a suitable source of water supply. For securing the pipe 31 in rigid position, inner and outer nuts 34 may be screw threadedly engaged with the 10 pipe 31 adjacent the cap 12.

The pipe 31, at that end thereof adjacent the plug 13 is provided with a substantially L-shaped branch 35 provided at its discharge end with a suitable valve 36.

15 Threaded into the passage 30 in the plug 13 is a screen 37.

From the description of the invention thus far it will be seen that with valve core 22 turned so that ports 24, 25 are out of registry, and ports 28, 29 are in registry, soap-suds, a chemical solution or other cleansing agent within the chamber 27 will pass through the screen 37, passage 30 and the valve core 22 on to the bristles of the brush 25 10 thus facilitating the application of a cleansing agent to the surface being scoured.

With the valve core 22 rotated so as to register port 24 with port 25, and move port 28 out of registry with port 29, water from 10 any suitable source of supply will pass from the pipe 31 through passage 26 and the valve core on to the brush, and the surface being cleansed, and the water coming directly from the source of supply will be clean and clear 35 and can be used for rinsing purposes subsequent to the scouring of the surface.

In actual practice the soap, chemical solution, or other cleansing agent is placed in the chamber 27 by first removing the cap 40 12. In the event soap is placed in the chamber 27, water may be supplied to the chamber 27 through the pipe 31, branch 35 and valve 36 to work up a suitable suds within the chamber 27 for cleaning purposes.

45 To facilitate rotation of the valve core 22, there is provided a handle member 38 that is equipped with a squared opening for accommodating the squared end of the stem 21 of the valve core.

50 Even though I have herein shown and described the preferred embodiment of the invention, it is to be understood that the same is susceptible of further changes, modifications and improvements coming within the 55 scope of the appended claims.

Having thus described my invention, what I claim as new is:

1. In combination, a brush having a back-

ing provided with an aperture, a handle for the brush provided with a fluid chamber, and a discharge passage leading from said chamber, of means for detachably securing the handle to the backing of the brush head including a valve casing extending diagonally through the handle and having ends projecting from the handle in reverse directions, one of the ends of said casing extending through the aperture in the back of the brush head, a nut threadedly engaged with said one end of the valve casing and coacting with the proximate end of the handle for securing the handle to the brush head, said valve casing at said one end being also open for discharging liquid on to the bristles of the brush head, and a hollow valve member rotatably mounted in the casing, said hollow valve member being open at one end, and being also provided with a lateral opening for movement into and out of registry with said passage for controlling the discharge of liquid from said chamber on to the bristles of the brush head.

2. In a brush, in combination, a brush head, a handle secured at one end thereof to the head, and provided with a soap chamber, a valve casing extending diagonally through the handle and projecting at one end through the brush head, a pair of passages provided in the handle and extending from one end of the soap chamber to the valve casing, spaced ports provided in the valve casing aligning with said passages, a valve core rotatably mounted in the valve casing and open at one end for the passage of fluid therethrough on to the bristles of the brush head, said valve core being provided with ports on diametrically opposite sides thereof for registry with the ports in the valve casing whereby when one of the ports in the valve stem is in registry with one of the ports in the valve casing, the other of the ports in the valve stem will be out of registry with the other of the ports in the valve casing, a conduit extending through the handle and connected at one end with one of said passages and being provided adjacent said one end with a discharge branch extending into the soap chamber, said discharge branch having a control valve associated with the discharge end thereof, whereby when the valve core is rotated for moving the ports of the core out of registry with the ports of the valve casing to close said passages, fluid passing through said conduit will be forced into the soap chamber.

FRED C. WHITE.
